UNITED STATES PATENT OFFICE.

JOSEPH WHITECAR, OF PHILADELPHIA, PENNSYLVANIA.

IMPROVEMENT IN HOISTING OYSTER-DREDGES.

Specification forming part of Letters Patent No. **38,436**, dated May 5, 1863.

To all whom it may concern:

Be it known that I, JOSEPH WHITECAR, of the city and county of Philadelphia, and State of Pennsylvania, have invented a new and Improved Mode of Hoisting Oyster-Dredges; and I do hereby declare that the following is a full, clear, and exact description of the construction and operation of the same, reference being had to the annexed drawings, making a part of this specification, in which—

Figure 1 is a top view of the dredge and the device for hoisting the same. Fig. 2 is a side elevation of the same. Fig. 3 is an edge view of one of the studs or jambs D attached to a portion of the boat. Fig. 4 is a modification of one of the conical wheels A and a portion of the shaft B.

Like letters in all the figures represent the same parts.

The nature of my invention will be understood by the following description.

I arrange a pair of conical wheels, A A, on a shaft, B, whose journals C C turn in the studs or jambs D D, which project above the large diameters of the wheels as guides for the bottom side pieces, E E, of the dredge F, which rests upon the wheels as the dredge is drawn into the boat. The said wheels A A are of sufficient diameter on their large straight parts a a to cause the dredge to be so far elevated above the shaft B that the teeth b b b b shall not strike against the shaft B as they pass over the same.

Instead of having the two wheels on the same shaft, they may be placed on short independent shafts, if desired, by having additional bearings for their inside journals; and instead of having high jambs D D, as represented, the wheels may be constructed with a flange, e, as represented in Fig. 4, to act as guides instead of the jambs.

I have represented the dredge as made in

the usual way, but do not confine myself particularly to that construction, but contemplate extending the side pieces, E E, beyond the teeth b of the dredge, so as to rest upon the wheels A A after the teeth have passed over the shaft B, instead of having the parts d d to come upon the wheels; or there may be stationary pieces placed in front of the wheels for the ends of the shafts E E to slide upon after they have left the wheels. The said stationary pieces may be horizontal or inclined, and instead of having them fast in their places they may be portable, and of sufficient length to act as skids to take the dredge some distance on the boat or vessel, if desired.

It will readily be seen that when the front part of the dredge is drawn over the shaft B until it arrives at the position it assumes in Figs. 1 and 2, with the side pieces, E E, resting on the small part of the cone of the wheels A A, the said side pieces or shafts, E E, will come on the large straight parts a a of the wheels at the same time, and be guided laterally by the studs or jambs D D, which are placed just so far apart as to allow the dredge to pass between them easily.

Having thus fully described the construction and operation of the improved mode of hoisting oyster-dredges as invented or improved by me, what I claim therein as new, and desire to secure by Letters Patent, is—

Constructing and arranging a pair of conical wheels, substantially as described, in combination with an oyster or other dredge, for the purpose above set forth.

In testimony that the above is my invention I have hereunto set my hand and affixed my seal this 21st day of February, 1863.

JOSEPH WHITECAR. [L. S.]
